(57) **CLAIM**

The ornamental design for a combination fluid transfer apparatus, container, and support, as shown.

DESCRIPTION

FIG. 1 is a front perspective view of the combination fluid transfer apparatus, container, and support;

FIG. 2 is a front elevation view of the combination fluid transfer apparatus, container, and support;

FIG. 3 is a rear elevation view of the combination fluid transfer apparatus, container, and support;

FIG. 4 is a top plan view of the combination fluid transfer apparatus, container, and support;

FIG. 5 is a side elevation view of a first side of the combination fluid transfer apparatus, container, and support;

FIG. 6 is a side elevation view of a second side, opposite to the first side, of the combination fluid transfer apparatus, container, and support; and,

FIG. 7 is a bottom plan view of the combination fluid transfer apparatus, container, and support.

The hose is shown fragmented to indicate indeterminate length.
